UNITED STATES PATENT OFFICE.

GEORGE W. MULLER, OF WASHINGTON, DISTRICT OF COLUMBIA.

COMPOUND RAIL.

Application filed November 21, 1925. Serial No. 70,521.

To all whom it may concern:

Be it known that I, GEORGE W. MULLER, citizen of the United States, residing at Washington, in the District of Columbia, have invented certain new and useful Improvements in Compound Rails, of which the following is a specification.

This invention relates to improvements in railway rails, and has for one of its objects to provide a rail of laminated and continuous construction and without transverse joints, and consequently without clamp plates or like holding means.

Another object of the invention is to provide a device of this character including a reversible ball portion so that when one side of the ball is worn the bearing portion can be reversed to present the unworn portion to the action of the wheels of the rolling stock.

Another object of the invention is to provide a device of this character having improved means for holding the parts firmly locked together and prevented from vertical displacement.

The preferred embodiment of the invention is best represented in the accompanying drawings, in which:

Figures 1 to 9, inclusive, are transverse sections of various arrangements of the improved compound and laminated rail.

Figure 10 is a side elevation of a section of a body portion of the improved rail.

Figure 11 is a side elevation of a portion of a bearing portion of the improved rail.

Figure 12 is a plan view on a reduced scale, of a portion of one of the improved rails with the head or load carrying members in section on the line 12-12 of Figure 1.

The improved rail is constructed of a plurality of longitudinally directed members of uniform length, and arranged in series, the units of each series disposed end to end with their contiguous ends intermediate the ends of the adjoining units, whereby a continuous rail is produced and without transverse joints, thus eliminating clamp or fish plates, and providing a rail which will not be deflected by the rolling stock.

The improved rail comprises a plurality of body members each including a tie flange 10 of the usual form and an upstanding web

11, a bearing member including a ball portion 12 and a downwardly directed web 13, and a clamping plate member including an upstanding web 14 and an outwardly directed rib or foot portion 15. The clamping plate member is not shown in Figures 8 and 9.

The webs 11 and 13 engage face to face at one side of the latter, and the holding member 14 engages the other face of the web 13, as shown. The several members are of the same length, for instance, thirty feet, the members 10-11 disposed end to end, the members 12-13 disposed end to end, and the members 14-15 likewise disposed end to end.

The confronting ends of the bearing members 12-13 are located about one third of the length of the body members, or nearer one end thereof than the other, while the confronting ends of the holding members are located about two thirds of the length of the body members and one third the length of the bearing member. Thus if the rail units are each thirty feet long, which is the usual length of railway rails, the confronting ends of the several units will be located at ten foot intervals as illustrated in Figure 12.

Clamp bolts 16 are employed at suitable intervals to hold the units together.

By this means an efficient compound rail is produced and uniformly supported throughout for the entire length and insures a smooth running of the rolling stock and free from jolts and jars.

In Figures 1 to 9, inclusive, various forms of the rail units are shown.

In Figure 1 the web 11 is formed with a longitudinally directed channel or seat 17, while the holding member 14 is formed with a like longitudinal seat or channel 18, the seats adapted to receive outwardly directed beads 19 on the lower edge of the web 13.

The beads and the channels coact to effectually hold the bearing member from upward displacement and likewise relieve the clamp bolts from shearing strains.

In Figure 2 the web 13 of the bearing member is uniformly enlarged toward the lower edge and the opposite sides provided with longitudinally directed V-shaped serrations or grooves 17^a, and the confronting faces of the web 11 and the holding member

14 are provided respectively with corresponding serrations or grooves 18^a and 19^a to engage the grooves 17^a. By this arrangement the grip between the parts is materially strengthened and reinforced.

5 In Figure 3, the web 13 tapers in reversely curved lines toward the lower edge, and the confronting faces of the web 11 and the member 14 are correspondingly curved, and 10 the contacting faces provided with V-shaped channels or grooves, the same as in Figure 2.

15 In Figure 4 the channels or grooves are in truncated cone shape transversely, and in Figure 5 the channels or grooves are semi-circular.

18 In Figure 6 the channels or grooves are in saw tooth shape.

20 In Figures 2, 3 and 4, the tie flange portion 10 of the body is formed with a longitudinally directed seat 20 to receive the outer edge of the toe portion 15 of the clamping plate member, to provide an effectual support against lateral displacement.

25 In Figure 7, the tie flange portion 10 is provided with an undercut seat 21, and the terminal of the toe portion 15 is formed with a lip member 22 to enter the undercut seat, and thus provide effectual means for preventing vertical displacement.

30 In Figures 8 and 9, the web 13 is shown supported against the web 11 directly, and without employing the holding member 14-15.

35 In the structure illustrated in Figure 8, the V-shaped grooves or channels are employed, and in Figure 9, also the web 13 is shown with a single bead 19 to engage in the channel 17 of the web 11.

40 In Figures 1, 2, and 7, the upper edge of the web 11 is beveled upwardly and inwardly as shown at 23, the upper edge of the web 14 is also beveled upwardly and inwardly as shown at 23^a, while the lower faces of the ball portion 12, are beveled inwardly and upwardly as shown at 24, to correspond to and closely engage the beveled portions 23 and 23^a.

45 By this means the downward pressure exerted on the ball portions 12 of the rails creates an inwardly directed force to draw the portions 11 and 13 toward each other, and the greater the pressure the greater the grip, and spreading action is effectually eliminated.

50 In Figures 1, 2, 7, 8 and 9, the upper edge of the web 11 is reinforced by an outwardly projecting bead or rib 25, while the member 14, as shown in Figures 1, 2 and 7, is also provided with a like strengthening rib or bead 26.

55 From the foregoing it is believed that the construction, operation and advantages of the invention may be readily understood by those skilled in the art and it is obvious that changes may be made in the details dis-

closed without departing from the spirit of the invention as expressed in the appended claims.

Having thus described my invention, what I claim as new and desire to secure 70 by Letters Patent, is:—

1. A railway rail, formed of a plurality of separable body members, one of the said members having a flange or base adapted to rest upon a railroad tie, the said member 75 having a web portion provided with an inclined side, a load-carrying member having a head or ball forming the tread of the rail, the said load-carrying member having a wedge-shaped web arranged in contact with the said inclined side of the member first mentioned, clamping plate members arranged end to end and co-extensive with the length of the rails and constructed and arranged to bear against the other side of the web of the load-carrying member, and means for securing all the said members together.

2. A railway rail, formed of a plurality of 80 separable members, one of the said members having a base flange adapted to rest upon a railroad tie, the said member having also a web portion provided with an inclined side, a load-carrying member having a head or ball forming the tread of the rail, the said load-carrying member having a web arranged in contact with the said inclined side of the web of the first mentioned member, the said base flange of the member first mentioned having a recess in its upper surface 85 a clamping plate member having its lower portion engaging the said recess, and means for securing all the said members together.

3. A railway rail, formed of a plurality of 90 separable members, one of the said members having a base flange adapted to rest upon a railroad tie, the said member having also a web portion provided with an inclined side, a load-carrying member having a head or ball forming the tread of the rail, the said load-carrying member having a wedge-shaped web arranged in contact with the inclined side of the web of the member first mentioned, the said base flange of the first 95 mentioned member having a recess in its upper surface, a clamping plate member having an extended lower portion engaging the said recess, and means for securing all the said members together.

4. A railway rail, formed of a plurality of 100 separable members, one of the said members having a base flange adapted to rest upon a railroad tie, the said member having also a web portion, a load-carrying member having a head or ball forming the tread of the rail, the said load-carrying member having a downwardly extending web arranged in contact with the web of the member first 105 mentioned, the said base flange of the member first mentioned having an undercut 110

recess in its upper surface, a clamping plate member having its lower portion fitted in the said recess, and means for securing all the said members together.

5. A railway rail, formed of a plurality of separable members, one of the said members having a base flange adapted to rest upon a railroad tie, the said member having also a web portion, a load-carrying member having a head or ball forming the tread of the rail, the said load-carrying member having a downwardly extending web arranged in contact with the web of the member first mentioned, a clamping plate member, the top edges of the said web of the member first mentioned and of the said clamping plate member being inclined downwardly and outwardly, the said ball of the load carrying member having lower surfaces inclined downwardly and outwardly and arranged to engage the said inclined tops of the said web and clamping member whereby pressure upon the load-carrying member acts to force the web of the member first mentioned and the said clamping member towards each other, and means for securing all the said members together.

6. A railway rail, formed of a plurality of separable members, one of the said members having a base flange adapted to rest upon a railroad tie, the said member having also a web portion, a load-carrying member having a head or ball forming the tread of the rail, the said load-carrying member having a downwardly extending web arranged in contact with the said web of the member first mentioned, a clamping plate member,

the said flange of the member first mentioned having a recess in its upper surface, 40 the said clamping plate member having a lower portion engaging the said recess, the tops of the said web of the member first mentioned and of the said clamping member being inclined downwardly and outwardly, the said ball of the load-carrying member having lower surfaces arranged in engagement with the said inclined tops of the said web and clamping member whereby pressure upon the load-carrying member 50 acts to force the said members towards each other, and means for securing all the said members together.

7. A railway rail, formed of a plurality of separable members, one of the said members having a base flange adapted to rest upon a railroad tie, the said member having also a web portion provided with an inclined side, a load-carrying member having a head or ball forming the tread of the rail, 60 the said load-carrying member having a web arranged in contact with the said inclined side of the web of the said first mentioned member, the said base flange of the member first mentioned having a recess in its upper surface, clamping plate members arranged end to end in staggered relation to the joints of the said load-carrying members and co-extensive with the length of the rails and having lower portions engaging 70 the said recesses in the base flanges, and means for securing the said members together.

In testimony whereof I affix my signature.

GEORGE W. MULLER.
